UNITED STATES PATENT OFFICE.

PAUL KRASTIN, OF DETROIT, MICHIGAN, ASSIGNOR OF ONE-HALF TO JOHN C. WIDMAN, OF DETROIT, MICHIGAN.

DESIGN FOR A LAMP.

No. 39,484.

Specification for Design.

Patented Sept. 1, 1908.

Application filed June 3, 1908. Serial No. 436,488. Term of patent 3½ years.

To all whom it may concern:

Be it known that I, PAUL KRASTIN, a citizen of the United States of America, residing at Detroit, in the county of Wayne and State of Michigan, have invented a certain new, original, and ornamental Design for Lamps, of which the following is a specification, reference being had therein to the accompanying drawings, forming part thereof..

The figure is a plan view of a lamp, showing my new design.

I claim:

The ornamental design for a lamp, as shown.

PAUL KRASTIN.
